US00D753066S

(12) **United States Design Patent**
Sturgess et al.

(10) **Patent No.:** US D753,066 S
(45) **Date of Patent:** ** Apr. 5, 2016

(54) **ELECTRICAL CONTACT ELEMENTS**

(71) Applicants: **Mark Sturgess**, Basel (CH); **Falk Blumenroth**, Rheinfelden (DE); **Tom Ledermann**, Riehen (CH); **Lucas Wirz**, Basel (CH)

(72) Inventors: **Mark Sturgess**, Basel (CH); **Falk Blumenroth**, Rheinfelden (DE); **Tom Ledermann**, Riehen (CH); **Lucas Wirz**, Basel (CH)

(73) Assignee: **Multi-Holding AG**, Allschwil (CH)

(**) Term: **14 Years**

(21) Appl. No.: **29/467,371**

(22) Filed: **Sep. 18, 2013**

(30) **Foreign Application Priority Data**

Mar. 18, 2013 (WO) DM/080 649
Aug. 29, 2013 (WO) DM/081 656

(57) **CLAIM**

The ornamental design for a electrical contact elements, as shown and described.

DESCRIPTION

FIG. 1 is a front view of the electrical contact elements that I regard as my invention;

FIG. 2 is a top view thereof;

FIG. 3 is a rear view thereof;

FIG. 4 is a right hand side view thereof;

FIG. 5 is a left hand side view thereof;

FIG. 6 is a bottom view thereof;

FIG. 7 is a perspective view thereof from above; and

FIG. 8 is a perspective view thereof from below.

FIG. 9 is a front view of a second embodiment of the endless band electrical contact element that I regard as my invention;

FIG. 10 is a top view thereof;

FIG. 11 is a rear view thereof;

FIG. 12 is a right hand side view thereof;

FIG. 13 is a left hand side view thereof;

FIG. 14 is a bottom view thereof;

FIG. 15 is a perspective view thereof from above; and,

FIG. 16 is a perspective view thereof from below.

The broken lines showing portions of the electrical contact elements in FIGS. 1-8 of the drawings are included for the purpose of illustrating environmental structure and form no part of the claimed design.

1 Claim, 16 Drawing Sheets
